[57] CLAIM

The ornamental design for a buckle member, as shown and described.

DESCRIPTION

FIG. 1 is a top perspective view of a buckle member according to a first embodiment of the invention;

FIG. 2 is a top plan view of the buckle member of FIG. 1, the bottom plan view being identical;

FIG. 3 is a top perspective view of a buckle member showing a second embodiment of my new design; and, FIG. 4 is a top plan view of the buckle member of FIG. 3, the bottom plan view being identical.

The broken line portions of the figures are for illustrative purposes only and form no part of the claimed design.
